UNITED STATES PATENT OFFICE.

ANDREW J. KENNEDY, OF CHICAGO, ILLINOIS, ASSIGNOR TO PARKS BROS. & ROGERS, INC., OF PROVIDENCE, RHODE ISLAND, A CORPORATION OF RHODE ISLAND.

CUFF LINK.

Application filed January 12, 1925. Serial No. 1,728.

To all whom it may concern:

Be it known that I, ANDREW J. KENNEDY, a citizen of the United States, residing at Chicago, in the county of Cook and State 5 of Illinois, have invented certain new and useful Improvements in Cuff Links, of which the following is a specification.

This invention relates to improvements in cuff links, and more particularly to cuff 10 links of the type which comprises separable cuff buttons.

One object of the present invention is to provide a cuff link of the separable button type which may be very cheaply and 15 economically manufactured, as to the stems and interlocking coupling members thereof, from sheet-metal by means of a punch press. Another object is to provide an improved 20 cuff link wherein, when the buttons are assembled, they will be yieldably held at an angle to each other corresponding substantially with the natural slant of the sides of the cuff, and when in such position will be securely interlocked against accidental separation. Another object is to provide an 25 improved construction of cuff link consisting of separable cuff buttons which will not become disengaged when the cuff itself is drawn upwardly and tightened upon the 30 arm. Another object is to provide an improved construction of cuff link wherein the two cuff members may be readily guided into co-operative engagement when closing the cuff.

35 Other objects and attendant advantages of the invention will be apparent to persons skilled in the art as the same becomes better understood by reference to the following detailed description, taken in connection 40 with the accompanying drawing wherein I have illustrated a practical and approved embodiment of the invention and of the steps and operations involved in manufacturing the same, and in which—

45 Fig. 1 is a plan view of a sheet-metal blank from which the female coupling member and the U-shaped stem or post of one of the buttons is formed;

50 Fig. 2 is a plan view of Fig. 1 showing the legs of the post bent transversely to substantially semi-cylindrical form and swaged upwardly from the body of the blank;

55 Fig. 3 is an edge view of Fig. 2, looking from the left of the latter figure;

Fig. 4 is a view showing the body of the blank bent transversely to a substantially triangular form in cross-section to thereby create the hollow locking member, and the legs of the post brought thereby into substantially parallel position; 60

Fig. 5 is a plan view of a sheet-metal blank from which the male locking member and the U-shaped stem or post of the other button are formed; 65

Fig. 6 is an edge view of Fig. 5, but showing the legs of the post bent transversely to substantially semi-circular form in cross-section and swaged upwardly from the plane of the body of the blank; 70

Fig. 7 is a view showing the body of the blank folded upon itself and the legs brought into substantially parallel relation; 75

Fig. 8 is a perspective elevation of one of the two caps which are applied to the ends of the female coupling member;

Fig. 9 is a top plan view of Fig. 4 with the end caps applied to the female coupling member;

Fig. 10 is a view showing the completed buttons separated and in position to be interlocked by movement toward each other; 80

Fig. 11 is an elevation, at right angles to Fig. 10 showing the two buttons interlocked and inverted relatively to Fig. 10; 85

Fig. 12 is an enlarged view corresponding with Fig. 11, in section through the posts and coupling members and also showing a spring located in the hollow legs of one of the posts for yieldably interlocking the two coupling members and holding the buttons tilted at an angle to each other corresponding substantially with the natural slant of the sides of the cuff; and

Fig. 13 is an enlarged cross-section 95 through the assembled coupling members at one side of the stems or posts.

Referring to the drawings, 15 designates the rectangular flat body portion of a thin sheet-metal blank from which the hollow coupling member and the U-shaped stem or post of one of the buttons is formed. Integral with the opposite ends of the body 15 are tongues 16. In the body 15 is formed a longitudinal slot 17 and a transverse slot 18 100 intersecting the slot 17. On one edge of the slot 18, and lying on opposite sides respectively of the longitudinal slot 17, are a pair of lips 19, the function of which will hereinafter appear. In the edges of the 105

110

blank body 15 from which the tongues 16 extend are cut small notches 20 for a purpose hereinafter explained.

The blank thus formed is subjected to the operation of a suitable die press by which the tongues 16 are bent transversely into substantially semi-circular form and at the same time swaged upwardly from the body 15 of the blank, as shown in Fig. 3, thereby forming the legs 21 of a U-shaped stem or post; this operation slightly narrowing the body 15 and the longitudinal slot 17, as shown in Fig. 2. In a suitable die press the blank having the form shown in Figs. 2 and 3 is further operated upon to bend the flat body 15 transversely on the lines $x-x$ and $y-y$ (Fig. 1) into the triangular form shown in Figs. 4 and 12, thereby forming a hollow tubular locking member 22, with the legs 21 through their outer portions disposed parallel and together forming a U-shaped stem or post 24, and leaving the lips 19 upstanding on one side of the transverse slot 18. The open ends of the hollow locking member 22 thus formed are closed by a pair of flanged caps 25 (Fig. 8) which are pressed over the ends of the coupling member 22 and the edges of the flanges pressed or crimped into the notches 20 and the extreme ends of the transverse slot 18, whereby said caps are securely locked in place. The button head 26 is soldered or brazed to the free ends of the legs of the U-shaped stem 24. Lying within the hollow legs of the post 24 is a U-shaped wire spring 27 (Fig. 12).

The stem and male locking member of the co-operating button are formed from the flat sheet-metal blank shown in Fig. 5; the same comprising a flat body portion 28 of substantially rectangular form and preferably with its opposite end edges notched as shown at 29, and tongues 30 projecting from the other two edges of the body. In a suitable die press the tongues 30 of this blank are bent into substantially semi-circular form in cross-section and at the same time swaged upwardly at their inner ends from the body 28, thereby forming legs 31 of the U-shaped stem or post of the other button. In the same or another operation the body 28 is bent transversely on the line $z-z$ (Fig. 5) and folded upon itself, thereby creating the male locking member 32 which, as clearly shown in Fig. 10, presents on its inner or lower edge shoulders 33, and at the same time bringing the outer portions of the legs 31 into substantial parallelism to form the U-shaped stem or post 34 (Fig. 7). To the outer end of the post 34 is brazed or soldered the button head 35. The coupling member 32 is of a length and width sufficient to pass through the slot 18 of the coupling member of the other button.

The two buttons formed as above-described are, in use, engaged with the button

holes in the two sides of the cuff by passing the coupling members through the button holes and then turning the buttons ninety degrees, thereby causing the relatively wide stems or posts 24 and 34 to lie in and parallel with the button holes, with the two coupling members projecting on the inner sides of the button holes at a right angle to the latter so that they also act as guards to prevent the buttons from accidental displacement from the button holes. The two buttons are then pressed toward each other until the coupling member 32 registers with the slot 18 of the hollow coupling member, in which operation the upstanding lips 19 and the rims of the caps 25 serve to center and guide the coupling member 32 into register with the slot. As the coupling member 32 passes through the slot it meets and compresses the spring 27; and when the buttons are then tilted as shown in Figs. 11 and 12, the reaction of the spring on the free edge of the coupling member 32 locks the shoulders 33 of the coupling member 32 out of register with the slot 18 and in interlocking engagement with the inner surface of one corner of the hollow coupling member 22 beyond the slot 18, and holds the two buttons tilted at an angle to each other that corresponds to the natural angle of the sides of the cuff, and maintains the buttons in this position during wear of the link; the spring in this position not being under tension. To disengage the buttons it is necessary only to press on the inner edges of the button heads until the posts are substantially in line with each other, compressing the spring, which brings the coupling member 32 into register with the slot 18, whereupon the thrust of the spring forces the two buttons apart.

During this separating movement the engagement of the stem of the male coupling member with the slot 17 centers the male coupling member 32 relatively to the entrance and exit slot 19, so that the ends of said member do not catch beneath the end margins of the slot. The double stems prevent turning of the buttons in the button holes, maintaining the coupling members always in position to engage with each other.

In assembling the parts, the head 26 is preferably brazed to its stem before the spring is inserted to prevent injuring the temper of the spring by heat, and the spring 120 is then readily inserted through the slot 17 and pushed downwardly into the legs 24 of the stem.

It is believed that the foregoing description, in connection with the drawing, will make clear the novel structural feature, mode of manipulation, and advantages of the invention. Manifestly minor changes in respect of structural details may be resorted to without departing from the spirit of the 130

invention or sacrificing any of the advantages thereof. Hence, I reserve all such variations and modifications as fall within the spirit and purview of the appended claims.

I claim—

1. A cuff link comprising in combination separable cuff buttons, one of said buttons comprising a head, a stem, and a hollow coupling member, and the other button comprising a head, a stem, and a co-operating coupling member adapted to interlock within said hollow coupling member, said coupling members permitting relative movement of the buttons about one axis only, and means holding said buttons interlocked at an angle to each other.

2. A cuff link comprising in combination separable cuff buttons, one of said buttons comprising a head, a stem, and a hollow coupling member, and the other button comprising a head, a stem, and a co-operating coupling member adapted to interlock within said hollow coupling member, said coupling members permitting relative movement of the buttons about one axis only, and a spring yieldably holding said co-operating coupling member interlocked within said hollow coupling member to retain said buttons securely interlocked at an angle to each other.

3. A cuff link comprising in combination separable cuff buttons, one of said buttons comprising a head, a hollow stem, and a hollow slotted coupling member, and the other button comprising a head, a stem, and a co-operating coupling member adapted to pass through the slot of said hollow coupling member and interlock within the latter, and a spring within said hollow stem for yieldably holding said coupling members interlocked with said buttons tilted at an angle to each other.

4. A cuff link comprising in combination separable cuff buttons, one of said buttons comprising a head, a U-shaped stem, and a tubular slotted coupling member on and disposed at a right angle to the plane of said stem, and the other button comprising a head, a stem, and a co-operating coupling member adapted to pass through the slot of said tubular coupling member and interlock within the latter, and spring means engaging said co-operating coupling member in a manner to lock the same out of register with said slot with said buttons tilted about the axis of said tubular coupling member.

5. A cuff link comprising in combination separable cuff buttons, one of said buttons comprising a head, a U-shaped stem, and a tubular coupling member on and disposed at a right angle to the plane of said stem and formed with a longitudinal slot and a transverse slot intersecting said longitudinal slot,

and the other button comprising a head, a U-shaped stem, and a co-operating coupling member adapted to pass through the longitudinal slot of said tubular coupling member and interlock within the latter, and spring means engaging said co-operating coupling member in a manner to lock the same out of register with said longitudinal slot and hold the stem of said co-operating coupling member in said transverse slot.

6. A cuff link comprising in combination separable cuff buttons, one of said buttons comprising a head, a U-shaped stem having hollow legs, and a tubular slotted coupling member, and the other button comprising a head, a stem, and a co-operating coupling member adapted to pass through the slot of said tubular coupling member and interlock within the latter, and a bow spring disposed within the legs of said U-shaped stem abutting against said co-operating coupling member and yieldably holding said coupling members interlocked with said buttons tilted at an angle to each other.

7. A cuff link comprising in combination separable cuff buttons, one of said buttons comprising a head, a U-shaped stem having hollow legs, and a tubular slotted coupling member of triangular form in cross-section, and the other button comprising a head, a stem, and a co-operating coupling member adapted to pass through the slot of said tubular coupling member and formed with shoulders on either side of its stem, and a bow spring disposed within the legs of said U-shaped stem abutting against said co-operating coupling member and yieldably holding the shoulders of the latter against the inner surface of one corner of said tubular coupling member.

8. A cuff link comprising in combination separable cuff buttons, one of said buttons comprising a head, a stem, and a hollow slotted coupling member, and the other button comprising a head, a stem, and a co-operating coupling member adapted to pass through the slot of said hollow coupling member and interlock within the latter, and means on said hollow coupling member for centering and guiding said co-operating coupling member into said slot.

9. A cuff link comprising in combination separable cuff buttons, one of said buttons comprising a head, a stem, and a hollow slotted coupling member, and the other button comprising a head, a stem, and a co-operating coupling member adapted to pass through the hollow slot of said coupling member and interlock within the latter, and an upstanding lip on one edge of said slot serving to center and guide said co-operating coupling member into said slot.
